CLAIM

The ornamental design for a hot air corn popper, as shown and described.

DESCRIPTION

FIG. 1 is a top, front, and left side perspective view of a hot air corn popper showing our new design;

FIG. 2 is a right side elevational view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a top, front, and left side perspective view of a modification of our new design;

FIG. 8 is a right side elevational view thereof;

FIG. 9 is a top plan view thereof;

FIG. 10 is a bottom plan view thereof;

FIG. 11 is a front elevational view thereof; and

FIG. 12 is a rear elevational view thereof.
